UNITED STATES PATENT OFFICE.

LEOPOLD KACZANDER, OF NEW YORK, N. Y., ASSIGNOR TO THE NATHAN MANUFACTURING COMPANY, OF SAME PLACE.

LUBRICATOR.

SPECIFICATION forming part of Letters Patent No. 357,931, dated February 15, 1887.

Application filed October 21, 1886. Serial No. 216,854. (No model.)

To all whom it may concern:

Be it known that I, LEOPOLD KACZANDER, of the city, county, and State of New York, have invented certain new and useful Improvements in Lubricators, of which the following is a specification.

My invention relates to that class of lubricators (designed more particularly for use on locomotives) in which the oil-chamber is combined with a condensing-chamber in which steam is condensed, and from which the resulting water of condensation is caused to pass gradually to the oil-chamber, for the purpose of effecting the feed of the lubricant.

More particularly, my invention is an improvement on that kind of lubricator of which the one set forth in Letters Patent of the United States No. 179,226, granted to Nicholas Seibert, of June 27, 1876, may be considered the type; and its object is to reduce the cost of construction, to facilitate the process of manufacture, and to secure a device of increased simplicity, effectiveness, and convenience. In this connection I would state that my lubricator is intended to be a double one—that is to say, one in which the same oil-chamber serves to lubricate both cylinders of a locomotive-engine; and it is with this end in view that my improvements have mainly been designed. I remark here, however, that some of said improvements are equally applicable to a "single" lubricator, or one which feeds only a single cylinder or other part.

In the accompanying drawings I have represented a lubricator which embodies the several features of my invention in their preferred form, and to these drawings I shall now refer in order to explain more clearly the nature of the invention and the manner in which the same is or may be carried into effect.

Figure 1 is a vertical central section of the lubricator on line 1 1, Fig. 3. Fig. 2 is a like section on line 2 2, Fig. 3. Fig. 3 is a horizontal section on line 3 3, Fig. 1, omitting the sight-feed tubes and their connections and the oil-gage. Fig. 4 is a section on line 4 4, Fig. 1, of one of the upper sight-feed-tube connections, omitting the hand-oiler. Fig. 5 is a section of the same sight-feed-tube connection, together with the hand-oiler, on line 5 5, Fig. 1. Fig. 6 is a side elevation of the complete

lubricator, together with its boiler-connections.

I shall first give a general description of the lubricator, and then point out the features which are of my invention.

A is the oil-reservoir. B⁵ is the condenser surmounting said reservoir and communicating with the same by the passages w' w² w³, through which the water of condensation (as permitted by the valve w) passes from the condenser to the lower part of the oil-reservoir.

S is the main steam-pipe leading from the boiler (see Fig. 6) to the top of the condenser, where it connects with the neck c.

S' is the steam-valve for the pipe S.

Within the condenser are two independent pipes, p and p', which extend up nearly to the top of the condenser, and at their upper ends are provided with openings for the entrance of steam from the condenser. Each pipe screws into the bottom of the condenser—that is to say, into the top of the oil-reservoir—and there communicates with a passage, s or s'. These passages which are formed in the top of the oil-reservoir are entirely distinct and separate and have no communication with each other. The one s leads to the upper sight-feed connection, B, and the other, s', leads to the upper sight-feed connection, B'. Each of these connections is like the other, so that a description of one will answer for both.

Referring to the connection shown in section in Figs. 4 and 5, it is provided with a horizontal passage, n² n, from its inlet to its exit, where is located the oil-exit pipe c², and with a screw-valve, B², which controls the opening through which the ascending oil passes from the sight-feed tube on its way to the pipe c². This valve is neither a throttling nor a regulating valve, but is simply a shut-off valve, its only and exclusive function being to prevent the escape of steam from the passage s or s', or from either of the pipes c², through the sight-feed glass or tube in case the latter should break. In other words, it is a mere safety appliance, which does not influence the normal working of the lubricator, and whether open (as represented in Fig. 1) or closed, (as represented in Fig. 5,) or, in fact, in any position, it does not interfere with free communication between the two portions n²

n of the horizontal passage, this being due to the fact that the plug on its end, which, when screwed down, stops the upper opening of the sight-feed tube, is not of a size to fill the passage 5 between *n*² and *n*. The connection is also provided with a lateral extension-neck, *n*³, designed to receive a common stationary hand-oiler, *H*, of well-known construction, provided with an oil-cup, *h*, and a regulating-valve, *h'*. 10 The neck *n*³ communicates by an independent passage, *n'*, with the oil discharge or exit pipe *c'*.

With each upper sight-feed connection, *B* or *B'*, is combined a lower sight-feed connection, *B*², having the usual feed-nozzle, *f*, and regulating-valve *R*.

K is the sight-feed tube intermediate between the two connections.

On the bottom of the oil-reservoir is the single cross-channel *O'*, which connects the two lower sight-feed connections, and into this channel enters the lower end of the oil-feed pipe *O*, which leads from the upper part of the oil-chamber.

25 *F* is the filling-plug.

W is the drain-cock.

G is the indicator commonly employed to show the amount of oil in the oil reservoir.

The operation of the lubricator is as follows:

30 Opening the steam-valve *S'*, steam from the boiler enters the condenser, and the water of condensation resulting therefrom is led by passages *w' w² w³* to the bottom of the oil-reservoir. The displaced oil passes over into the 35 pipe *O* at its top and is led into the single straight cross-channel *O'*, whence it is distributed to both of the lower sight-feed connections. The oil passing the feed-valves *R* and nozzles *f* ascends, drop by drop, through the 40 water in the visible-feed tubes, and finally passes out through passages *n* into the discharge-pipes *c'*, which connect with the parts to be lubricated. I remark here that when steam is turned on it passes through the parts *p* 45 and *p'*, and by its condensation fills the sight-feed tubes with water. At the same time that the oil is fed, as above described, jets of steam pass from the condenser through the passages *p s n² n* and *p' s' n² n* into the discharge-pipes, 50 exerting a balancing pressure directly on top of the oil in the sight-feed glasses, so that the oil is pressed through the passages *n* simply by the weight of the water-column in *w' w² w³* and the condenser.

55 I have already called attention to the fact that the steam conduits or passages *s s'* are separate and distinct from each other and have no connection whatever with each other save such communication as may be afforded by way of 60 the condenser, into which both of the pipes *p* and *p'* open. This I deem to be a valuable feature of my improvements, because by this arrangement the two sides of the lubricator can act independently of each other, which would not 65 be the case were such passages arranged (as has been heretofore suggested by others) to directly communicate with each other. It will

also be seen that by reason of the cross-channel *O'*, I am enabled to employ only one oil-pipe for the distribution of oil to the opposite 70 sides of the lubricator, which greatly simplifies the construction.

In the normal operation of the lubricator the valves *B²* are of course wide open, as shown in Fig. 1; but if one of the sight-feed glasses 75 should break then the valve *B²* appertaining to the broken glass should be closed, as shown in Fig. 5, thus closing communication between the glass and both the conduits *s* or *s'*, as the case may be, on the one hand, and the glass 80 and the discharge-pipe *c'* on the other hand, but at the same time leaving open communication between *s* or *s'* and *c'*. Under these conditions (the sight-feed being disabled) I can make use of the hand-oiler for lubricating 85 purposes, as follows, it being of course understood that it can only be used when steam is shut off from the cylinders, as it is, for instance, when the engine is going downgrade:

I fill the cup with oil, and then upon opening the valve *h'* oil will flow through the extension-neck *n*³ and by-passage *n'* into the discharge-pipe *c'*. Then I close the valve *h'* and open steam-valve *S'* for a moment, which will send a jet of steam, through *p s* or *p' s'*, as the case may be, and *n² n*, into the discharge-pipe, carrying the oil from the hand-oiler along with it. In this way it is feasible to use a steam-jet in connection with the hand-oiler, and this I deem a feature of value, which is applicable 90 to either a double or a single lubricator.

In conclusion I state that I am aware that in various modifications of the lubricating apparatus of which the patented Seibert lubricator, hereinbefore referred to, is the type, the lubricators have been constructed with auxiliary steam-jets wholly or partially within the confines of the body of the lubricator; and I am also aware that lubricators in combination with hand-oilers have been made before. I claim 105 none of these features, broadly.

I am also aware that the auxiliary steam-conduit has been so constructed and arranged that it will discharge its jet of steam into the passage leading to the oil-exit at a point beyond the upper end of the visible-feed tube and between the latter and the oil-exit. In my improved lubricator, on the contrary, the auxiliary steam-conduit is so arranged that the steam passing therefrom to the oil-exit is 115 discharged directly over the open top of the visible sight glass or tube, producing a very efficient balancing action.

Having now described my improvements and the preferred way of carrying the same 125 into effect, what I claim, and desire to secure by Letters Patent, is—

1. The combination of the oil-reservoir, the condenser, the two sight-feed tubes and their connections, the two oil-exit pipes, and auxiliary conduits leading from the condenser to the upper sight-feed connections for discharging steam into the oil-exits directly over the upper ends of the visible-feed tubes, the parts 130

being so arranged that the upper ends of the sight-feed tubes are between the oil-exit pipes and the discharge ends of the auxiliary steam-conduits, substantially as and for the purposes hereinbefore set forth.

5. The combination of the oil-reservoir, the condenser, the two visible-feed tubes and their connections, the oil-exit pipes, and two separate and independent auxiliary steam-conduits having no communication with each other and discharging steam from the condenser each into its appropriate oil-exit pipe, substantially as and for the purposes hereinbefore set forth.

10. The combination of the oil-reservoir, the condenser, the two visible-feed tubes and their connections, the two separate and independent auxiliary steam-conduits connected each with its appropriate upper sight-feed connection, the oil-pipe O, and the single cross-channel O', through which oil is supplied to both of the lower sight-feed connections, substantially as and for the purposes hereinbefore set forth.

15. The upper sight-feed connection formed with a passage for connecting the auxiliary steam-conduit and the oil-exit pipe, in combination with the sight-feed tube and the screw-valve B², movable toward and away from the

sight-feed tube and constructed and arranged to open and close the upper end of said tube without closing said passage, as and for the 30 purposes hereinbefore set forth.

20. The combination of the oil-reservoir, the sight-feed tube, and its lower connection with the upper sight-feed connection provided with two independent oil-outlet passages—the one 35 for oil from the reservoir, the other for oil from a hand-oiler—the condenser and auxiliary steam-conduit leading therefrom to said upper sight-feed connection, and the auxiliary hand-oiler, under the arrangement and for operation 40 substantially as hereinbefore set forth.

25. The upper sight-feed connection provided with passage n² n, by-passage n', neck n³, oiler H, and valve B², in combination with the sight-feed tube and its lower connection, the oil-reservoir, the condenser, and the auxiliary steam-conduit, as and for the purposes hereinbefore set forth.

In testimony whereof I have hereunto set my hand this 15th day of October, 1886.

LEOPOLD KACZANDER.
